Int. Cl. D12—08

U.S. Cl. D12—91

FIG. 1

FIG. 2

FIG. 3

FIG. 4

FIG. 5

FIG. 1 is a rear perspective view of a station wagon body showing my new design.

FIG. 2 is a front perspective view thereof.

FIG. 3 is a front elevational view thereof.

FIG. 4 is a rear elevational view thereof.

FIG. 5 is a rear perspective view of a station wagon body showing a second embodiment of my new design wherein the differences reside in the omission of the rear side windows and the configuration of the rear bumper and the addition of a rear-view mirror.

The side of the station wagon body not shown in FIGS. 1, 2 and 5 is the same as and symmetrical with the sides shown therein.

I claim:

The ornamental design for a station wagon body, as shown and described.
